Primary Examiner—Doris Clark
Attorney, Agent, or Firm—Frank G. Morkunas[57] **CLAIM**

We claim the ornamental design for the vertically disposed earthquake-resistant and absorption bridge and building support, as shown and described.

DESCRIPTION

FIG. 1 is a perspective view of a vertically disposed earthquake-resistant and absorption bridge and building support showing our new design;

FIG. 2 is an elevation view of the left-side member thereof the right side member being a mirror image of the left side member.

FIG. 3 is a top plan view thereof.

FIG. 4 is a rear elevation view thereof.

FIG. 5 is a front elevation view thereof; and,

FIG. 6 is a bottom view thereof.
